UNITED STATES PATENT OFFICE.

CHARLES T. INMAN AND HENRY A. ROBINSON, OF AKRON, OHIO.

CONCRETE-REINFORCING MEMBER.

1,050,834.

Specification of Letters Patent. Patented Jan. 21, 1913.

Application filed February 18, 1907. Serial No. 358,057.

To all whom it may concern:

Be it known that we, CHARLES T. INMAN and HENRY A. ROBINSON, citizens of the United States, residing at Akron, in the 5 county of Summit and State of Ohio, have invented new and useful Improvements in Concrete-Reinforcing Members, of which the following is a specification.

As the object of this invention, it will 10 be stated that in the construction of concrete work it frequently happens that it is necessary to lap the mechanical elements employed for strengthening purposes, and under certain conditions it is requisite that 15 the various binders employed in a given work intersect each other and engage each other sufficiently firmly to unite the entire mass into an integral body. In view of the foregoing it therefore becomes an essential 20 element of this invention that the means for connecting the various portions of the binder together, either when they are lapped or when they intersect each other, be of such a configuration that they will unite with 25 each other without a reformation of the bar or the necessity of making the same of a particular shape to fit a particular piece of work; in other words, to make the fastening or interlocking feature of the bar of a 30 universal pattern which will make its use adaptable to any contingency, thereby supplying a universal locking device capable of uniting a plurality of elements, as well as 35 serving the purpose of perfect engagement with the concrete material in which the same is embedded.

A practical embodiment of our invention 40 is illustrated in the accompanying drawing in which similar reference numerals indicate like parts.

Figure 1 is a perspective view of a portion of a bar embodying our invention, and Fig. 2 is a perspective view of a portion of 45 a plurality of bars, each bar in accordance with our invention, illustrating the manner in which duplicate bars extending in planes intersecting each other at an angle may be interlocked.

It will be stated before giving a specific 50 description of the invention, that the interlocking feature which forms a primary object of this invention is applicable to any bar in which the transverse dimensions are approximately equal, thereby making its 55 use substantially universal in all contingencies. In order to illustrate, there is

shown in the drawing, a bar substantially square in cross-section, having formed on each face a plurality of regularly recurring depressions and protuberances or lugs, preferably alternating with each other in each surface, and formed along the medial line of each face of the bar and spaced apart from the side edges of such faces. As shown, the reference numeral 2 designates 60 depressions on one side of the bar, and 5 the protuberance. On the opposite side of the bar, the depressions are designated by the reference numeral 10, and the protuberances by the reference numeral 9, so that 70 opposite the depressions 2, are protuberances 9, and opposite the protuberances 9 are depressions 2. The protuberances and depressions are of identical contour and size and are preferably made circular and are 75 each given a slight bevel in order to make their manufacture and use easier; but they may be made perfectly cylindrical without departing from the scope of this invention. In view of the fact that these depressions 80 and protuberances are of identical size, two bars of the same contour may be lapped and the protuberances of one bar will nicely fit in the depressions of a complementary bar and engage therewith a sufficient tenacity as 85 to prevent their accidental release; especially, when supplemented by the fact that the lapped bars are surrounded by an inclosing mass of concrete.

The drawing shows a bar wherein the 90 transverse diameters are substantially equal, and the same description in relation to the formation of protuberances and depressions already given, applies to the remaining two opposite sides of the bar, the depressions 95 6 on one side being opposite the protuberances 7 on the opposite side.

As will be seen, the facial configuration of two contiguous faces is similar with respect to the protuberances or projections 100 and depressions, the difference being however, that the positions of the projections and depressions are so arranged that these elements are out of cross-sectional alinement, the elements of one face being inter-spaced with respect to the elements of the adjacent face, the constant cross-section of the bar however, providing that opposite faces have the elements in cross-sectional alinement. By this particular arrangement, 105 it will be readily understood and as illustrated in Fig. 2 that either of any two

contiguous faces of the bar may have interengagement with a similar face of a corresponding bar and by interlocking either longitudinally of or at an angle to such face, the planes of contiguous faces however, intersecting each other at an angle so that the bar may act as a support for two bars each engaging the bar, but having the engagement with different contiguous faces and extending in such intersecting planes. The bar as above described therefore differs from the prior known devices in bar form, in which projections and depressions constitute practically the entire face of the bar, and also differs from the prior known devices in bar form, since in our invention the bar has more than two faces, and any face of the bar may be interlocked with any face of a duplicate bar, either longitudinally or at an angle.

What we claim and desire to secure by Letters Patent, is:—

1. A reinforcing member for concrete construction comprising a bar having more than two faces, two contiguous faces thereof being plane surfaced and each having equally-spaced projections and depressions

of similar configuration and size in alternating arrangement, each face of the bar being in the plane of the bases of the projections on said face, the projections and depressions of one face being out of cross-sectional alinement with those of the contiguous faces.

2. A reinforced member for concrete construction comprising a bar having more than two faces, each face being plane surfaced and having equally-spaced projections and depressions of similar configuration and size in alternating arrangement, each face of the bar being in the plane of the bases of the projections on said face, the projections and depressions of one face being out of cross-sectional alinement with those of the contiguous faces.

In testimony whereof we have hereunto set our hands in presence of two subscribing witnesses.

CHARLES T. INMAN.
HENRY A. ROBINSON.
